TOWEL CABINET

Jacques Rousso, Los Angeles, Calif.

Application January 31, 1938, Serial No. 187,853

9 Claims. (Cl. 312—37)

This invention relates to towel cabinets or racks, and more especially to such cabinets of the individual towel type.

An object of the invention is to provide a simple, practical, and efficient device of the character described.

Another object is to provide improvements in individual towel cabinets or racks wherein the delivery and return of towels to and from the laundry may be expedited in a manner to prevent loss of the towels in transit.

Other objects and advantages will appear and be brought out more fully in the following specification, reference being had to the accompanying drawings, wherein:

Fig. 1 is a front view partly broken away, showing a towel cabinet involving my invention;

Fig. 2 is a sectional elevation taken along the line 2—2 of Fig. 1;

Fig. 3 is a fragmentary section taken along the line 3—3 of Fig. 2;

Fig. 4 is an enlarged view partly in section showing the retaining rod and associated parts;

Fig. 5 is a plan section taken along the line 5—5 of Fig. 4;

Fig. 6 is an elevation partly in section illustrating the retaining rod lock;

Fig. 7 is a top view taken along the line 7—7 of Fig. 4;

Fig. 8 is a sectional view taken along the line 8—8 of Fig. 4;

Fig. 9 is a bottom view taken along the line 9—9 of Fig. 4;

Fig. 10 is a separate side view of the lock collar;

Fig. 11 is a side view of the retaining rod;

Fig. 12 is a view of the key for the lock collar;

Fig. 13 is a view of the key for the lock shown in Figs. 4, 5, and 6; and

Fig. 14 is an enlarged view showing the lower end of the guide rod, the lock collar, and a portion of the used towels.

Referring more particularly to the drawings, I show a towel cabinet or rack 20 having a vertical frame portion 21, a hopper 22 having a base 23 on which a retaining plate 24 is suitably secured, the plate having an elongated slot 25 positioned over an enlarged aperture 26 in base 23. A shelf 27 is secured to frame 21 near the upper portion thereof and is provided with an aperture 28 adapted to receive a lock housing 29, the lock housing being secured to shelf 27 by a retaining plate 30 in which is located a rectangular aperture 31 which is adapted to receive the rectangular latch end portion 32 of a rigid retaining rod

33 forming a part, displaceable or removable section of a guide rod, or member, extending between the shelf and hopper as will be later described, a stop collar forming a towel retaining abutment 34 being secured to rod 33 adjacent end portion 32 and plate 30 on the shelf 27 when the adjacent rectangular latch end portion 32 of the retaining rod 33 is anchored and locked in the lock housing 29 secured to the shelf 27 by the retaining plate 30 and thus to the shelf 27.

The foregoing structure is such that when the end 32 of the rod 33 is positioned in the lock housing 29, through aperture 31, the rod 33 is prevented from turning in the lock. Member 32 is provided with a locking abutment 35 and cam surface 36, the latter being adapted to coact with a lock latch 37 having a cam surface 38 and guide arms 39, and biased by spring 40 and operable by a key 41.

Referring more particularly to Fig. 4, the retaining rod 33 is shown as having a plurality of towels 42 secured thereto, each towel having a grommet 43 provided with an aperture 44 by which it is retained to the rod 33. Rod 33 has a locking groove 45 adjacent its upper end, and also a threaded recess or socket 46 and a tapered end portion 47. A locking collar 48 (Fig. 10) consists of a flanged lower disc 49 and an upper flanged disc 50, disc 49 having a flared aperture 51 and disc 50 having a flared aperture 52. Within the space formed by discs 49 and 50 is a lock unit (Figs. 7—9) comprising a bearing block 53 suitably secured within and to disc 49, block 53 being adapted to provide bearing seats or spaced recesses 54 for a pair of lock arms or tumblers 55 which in turn have arcuate or concavo convex portions 56 adapted to engage locking groove 45 and extension operating arms 57 adapted to be separated by a key 58, a key slot 59 being provided in disc 50 and a key guide aperture 60 in disc 49. A pair of springs 61 are suitably secured to block 53 and are adapted to press lock arms 55 together. The guide member or means includes the retaining rod or removable section or portion 33 and a guide rod 62, and said guide member or means extends between the horizontal support or shelf 27 and the hopper 22, and as illustrated, extends into the hopper to the base or bottom 23 thereof through which it is adapted to be anchored and held against turning as will now be described. The guide rod 62 (Figs. 1, 2, 3 and 14) is shown as having a flat sided end portion 63 adapted to be passed through the elongated slot 25 in plate 24 and through aperture 26 in a manner to prevent turning of the rod there-

55

in. A retaining collar 64 is secured to rod 62 a short distance from the lower end thereof and prevents the towels from being removed from the guide rod at the end 63. The upper end of rod 62 terminates in a goose neck 65 having a threaded end 66 for coupling with threaded recess 46 of retaining rod 33.

The operation of the invention should be apparent from the foregoing description. A supply of towels 42, definite in number, for instance fifty or one hundred, will be delivered from the laundry mounted on a rigid retaining rod 33 with the lock collar 48 locked to groove 45. Rod 33 can then be easily joined to the threaded end 66 of guide rod 62 and the end portion 63 of rod 62 slipped into place in slot 25 and the latch end portion 32 of rod 33 secured in lock housing 29. Collar 48 is thereupon released from groove 45 and passed upwardly around goose neck 65 and permitted to drop into hopper 22 adjacent collar 64 (Fig. 14). The towels may now be used in the ordinary manner, and when all have been used, they are returned to rod 33 and lock collar 48 locked into groove 45. The lower end 32 of rod 33 may now be released from lock 29 and rod 33 unscrewed from guide rod 62. The towels may now be returned to the laundry without the necessity of counting and with the certainty that all which were delivered are being returned, and a fresh supply substituted in the same manner.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a towel rack of the class described, a fixedly mounted lock housing and key operated lock therein, and a hopper for used towels, a rigid guide means for towels extending from said lock housing into said hopper to prevent displacement of the towels for misuse, said guide means having a section detachably connected to and bodily removable from the remainder of the guide means and lock housing, and adapted to hold a plurality of clean towels, and means for locking the towels on said removable section for transportation to and from a laundry.

2. In a towel rack of the class described, a fixedly mounted lock housing and key operated lock therein, and a hopper for used towels, a rigid guide means for towels extending from said lock housing into said hopper to prevent displacement of the towels for misuse, said guide means having a section detachably connected at one end to said lock housing and at the other end to the end of the adjacent section of the guide means, and means for locking the towels on said detachable section for transportation to and from a laundry.

3. A towel rack of the class described, including a shelf for clean towels and a hopper for the used towels, in combination with a rigid guide means extending upwardly from said shelf and then downwardly into said hopper, said guide means having a section detachably connected to and bodily removable from the remainder of said means, and means for locking a plurality of towels on said removable section for transportation to and from a laundry.

4. A towel rack of the class described, including a shelf for clean towels and a hopper for the used towels, in combination with a guide means extending upwardly from said shelf and then downwardly into said hopper, said guide means being rigid throughout its extent and having a terminal section detachably connected at one end to said shelf and at the other end to the end of the adjacent section of the guide means, and means for locking a plurality of towels on said detachable terminal section for transportation to and from a laundry.

5. A towel rack of the class described, including a shelf for clean towels and a hopper for the used towels, in combination with a rigid guide means extending upwardly from said shelf and then downwardly into said hopper, said guide means comprising a main section and a detachable terminal section, a threaded connection between the adjacent ends of said sections, the terminal section having a non-circular lower end, a non-circular socket in said shelf to receive said lower end of the terminal section, and means for locking a plurality of towels on said terminal section for transportation to and from a laundry.

6. A towel rack of the class described including a shelf for clean towels and a hopper for the used towels, in combination with a guide means extending upwardly from said shelf and then downwardly into said hopper, said guide means comprising a main section and a detachable terminal section, a threaded connection between the adjacent ends of said sections, the terminal section having a non-circular lower end, a non-circular socket in said shelf to receive said lower end of the terminal section, and means for locking a plurality of towels on said terminal section for transportation to and from a laundry.

7. A towel rack of the class described, including a shelf for clean towels and a hopper for the used towels, in combination with a guide means extending upwardly from said shelf and then downwardly into said hopper, said guide means comprising a main section and a detachable terminal section, a threaded connection between the adjacent ends of said sections, said terminal section having a non-circular lower end, a non-circular socket in said shelf to receive said lower end of the terminal section, an abutment on said terminal section above said non-circular end, and a locking collar on the upper end of said section adapted when in place thereon to lock a plurality of towels on the terminal section for removal, and when released, to slide on to the main section of the guide means to permit the towels to be moved from the shelf to the hopper.

8. A towel rack of the class described, including a shelf for clean towels and a hopper for the used towels, in combination with a guide means extending upwardly from said shelf and then downwardly into said hopper, said guide rod comprising a main section and a terminal section, a threaded connection between the adjacent ends of said sections, said terminal section having a non-circular lower end, a non-circular socket in said shelf to receive said lower end of the terminal section, an abutment on said terminal section above said non-circular end, and a locking collar on the upper end of said section adapted when in place thereon to lock a plurality of towels on the terminal section for removal, and when released, to slide on to the main section of the

guide means to permit the towels to be moved from the shelf to the hopper, said collar having a key operated tumbler and a groove in said terminal section to receive said tumbler.

9. A towel rack of the class described, including a shelf for clean towels and a hopper for the used towels, in combination with a guide means extending upwardly from said shelf and then downwardly into said hopper, said guide means comprising a main section and a detachable terminal section, a threaded connection between the adjacent ends of said sections, said terminal section having a non-circular lower end, a non-cir-

cular socket in said shelf to receive said lower end of terminal section, a locking device on said shelf adapted to lock the terminal section thereto when said non-circular end is moved into said socket, an abutment on said terminal section above said non-circular end and a locking collar on the upper end of said section adapted when in place thereon to lock a plurality of towels on said section, and to slide on to the main section of the guide means to permit the towels to be moved from the shelf to the hopper.

JACQUES ROUSSO.
